UNITED STATES PATENT OFFICE.

NATHAN T. FITCH, OF CHICAGO, ILLINOIS.

INSULATOR.

SPECIFICATION forming part of Letters Patent No. 349,783, dated September 28, 1886.

Application filed March 6, 1884. Renewed July 26, 1886. Serial No. 209,188. (No model.)

To all whom it may concern:

Be it known that I, NATHAN T. FITCH, a citizen of the United States, residing at Chicago, in the county of Cook and State of Illinois, have invented certain new and useful Improvements in Insulators; and I hereby declare the following to be a full, clear, and exact description of the same.

My invention relates to the class of insulators which are used to support telegraph, telephone, and electric-light wires, and are secured for that purpose by means of metallic screws upon suitable supports.

It has hitherto been the practice to provide the insulator with an opening extending longitudinally through its center, and of dimensions adapted to receive the shank of a screw, in which the screw-head forms a stop to prevent passage of the screw through the opening, the screw-threaded portion projecting beyond the insulator to afford a means for securing it upon a support. This construction makes the device undesirable, inasmuch as the screw-head, being exposed, provides a conducting medium for the electric current when the insulator is exposed to damp or wet weather, whereby a film of moisture forms upon it and affords a conducting-surface for the current from the wire to the screw-head, whence it passes to the ground upon the moist surface of the insulator-support and the post.

It is my object to prevent leading of the current, through the medium of the securing device, from its course upon the wire; and to this end my invention consists in an insulator provided with a screw or analogous securing device, the said securing device being embedded throughout a part of its extent within the material forming the insulator, thus becoming incorporated with it and affording a strengthening medium, and projecting to the remainder of its extent beyond the insulator.

In the drawings, Figure 1 is a perspective view of an insulator provided with my improvement. Figs. 2, 3, 4, and 5 are vertical sections of the same, showing modifications.

A is the body of the insulator, formed of insulating material, preferably of the compound

described and claimed in the J. P. Martin patent, No. 282,914, August 7, 1883. 50

B is a metallic screw, having its shank embedded within the insulator in the process of molding the same, the threaded portion projecting beyond it. The screw should be of a length sufficient to permit it to penetrate nearly to the top surface of the insulator, leaving a projecting portion sufficient to secure the device firmly upon its support. The embedding of a considerable portion of the length of the screw within the material forming the insulator is desirable under all circumstances, since the largest friction-surface is obtained, thus insuring rigidity of the screw in position; but it is particularly desirable, as the material forming the insulators embodying my improvement, like that hereinbefore specifically referred to, is frangible, since, being necessarily weakened to a certain extent by the groove formed upon it, the screw, by extending above the groove, affords a strengthening medium, 70 and prevents separation by fracture of the upper portion.

Various forms may be provided for the portion of the screw contained within the insulator, that represented in Fig. 2 being of quadrangular shape, in Fig. 3 a common headed screw. In Fig. 4 a screw having a T-shaped head is shown, and Fig. 5 represents the screw as flattened toward its upper end to increase the friction-surface. Other forms—for example, that of an L-shaped head or of a lag-screw—present advantages equally desirable with those above described. The object being to prevent the passage of the current from the wire down the securing device, it is obvious that the same may also be effected with insulators provided with openings extending through them by filling the opening, after the insertion of the securing device, with paraffine, sealing-wax, or other insulating substance. This mode possesses disadvantages, however, and is therefore not the most desirable. 85 90

The screw feature of the attaching mechanism, though the preferred form for use, is not absolutely essential, since other forms can be 95

devised that will render the device practicable.

What I claim as new, and desire to secure by Letters Patent, is—

- 5 The combination, with an insulator, A, of a screw, B, for securing the insulator upon its support, said screw being embedded throughout a part of its extent within the insulator;

extending therein above the groove *t*, to afford a strengthening medium for the insulator, and to project to the remainder of its extent beyond the insulator, substantially as described.

NATHAN T. FITCH.

In presence of—

THOMAS A. BANNING,
DOUGLAS DYRENFORTH.
